SKIVING MACHINE

Eugene J. Ray, Beverly, Mass., assignor to United
Shoe Machinery Corporation, Borough of
Flemington, N. J., a corporation of New Jersey

Application January 23, 1940, Serial No. 315,222
In Canada January 16, 1940

2 Claims. (Cl. 69—9.5)

This invention relates to skiving machines and is herein illustrated as embodied in a machine having a tubular knife, said machine being particularly adapted to skive pieces of sheet material, such as leather, which are to be incorporated in boots and shoes.

In machines of this general type, it is sometimes desirable, when changing from one kind of work to another, to remove the feed roll and replace it with one of a different type, for example, to replace a feed roll having radial slots with a roll having a knurled surface; and hitherto it has been necessary to remove certain parts of the machine from their adjusted positions and then to readjust such parts in order to replace one feed roll with another. In accordance with the present invention, the whole feed roll assembly may readily be removed and replaced without disturbing any adjusted part of the machine.

Referring to the accompanying drawing,

Fig. 1 is a view looking down upon the working-engaging parts of a machine, in which the present invention is embodied, the overhanging arm with its work presser having been omitted, and parts of the main and auxiliary frames of the machine being shown in section;

Fig. 2 is an end elevation of the feed roll driving link; and

Fig. 3 is a detail, partly in section and partly in elevation, showing more particularly how the feed roll assembly is held in its carrier by a screw having a long head, which projects out through an opening in the frame of the machine.

The machine is of the general type shown in United States Letters Patent No. 1,469,849, granted October 9, 1923, upon an application filed in my name, in that it comprises a rotary tubular knife 4, a feed roll 9 located partly within the knife, and a presser, not shown, which holds the work support against the knife. The machine is an improvement upon the machine of my prior application Serial No. 268,718, filed April 19, 1939, the improved construction permitting ready removal of the feed roll assembly.

In the present machine, as in the machine of the application, the carrier 5 for the feed roll assembly is angularly movable about the axis of a stationary but longitudinally adjustable rod 7 and is acted upon by a spring, not shown, which tends at all times to swing the carrier up as far as a stop, not shown, will permit. This construction normally holds the carrier in the position shown, but permits the carrier, and with it the feed roll, to yield about the axis of the rod

1, thus providing for bodily yielding movement of the feed roll toward and from the operative portion of the edge of the knife. The feed roll is also mounted for angular or tilting movement about an inclined axis, which passes through a point z at one end of the uppermost element of the roll. To this end, the roll is rotatably mounted on the stem of a screw 11, the head, at the farther end of which as viewed in Fig. 3, being seated in a socket in the farther end of the feed roll. The near end of the screw is threaded into a split portion of a block 13 and is held firmly by a pinch screw 15. The block 13 has integral with it a cylindrical stem 17 rotatably mounted in a bore formed in the part of the feed roll carrier 5. The bore is inclined up from left to right, as viewed in Fig. 3, and its axis passes through point z (Fig. 1). A screw 19, threaded into one end of the stem 17, holds the stem in the inclined bore, this screw being somewhat different from that of the machine of the application. The roll is normally held in the angular position shown with respect to the inclined axis which passes through the point z, by a torsion spring 21 which is wound about a small rod 23, one end of the spring being fast to a collar 25 which is fastened to the rod. The other end of the spring extends beneath and exerts an upward pressure upon a member carried on the underside of the block 13, said torsion spring at all times urging the block 13, and with it the feed roll, upwardly about the axis of the stem 17 as far as a stop, not shown, on the carrier 5 will permit. The rod 23 may be turned about its longitudinal axis and locked in position to vary the force with which it tends to swing one end of the roll upward. The feed roll shown is slotted circumferentially, and a comb 27 mounted on the block 13 has teeth which enter the slots. The feed roll, as described above, is capable of yielding bodily up and down and of tilting about the inclined axis of the stem 17, such movements being imparted to it by pressure exerted upon it through the work by a presser foot, not shown. The feed roll is driven from the end of a rotatable shaft 29. The end of this shaft is provided with a socket and with aligned slots which intersect the socket to receive an enlarged end or ball and a cross pin 30 at one end of a small link 31, the other end of which has another ball and pin which are received in a socket and a slot in the adjacent end of the feed roll. In the machine of the application, the pins which correspond to the cross pins 30 are freely slideable in and out of bores in the balls at the ends of the link.

When it is desired to remove a feed roll as-

sembly and replace it by one having a different feed roll, the auxiliary frame 33 is unlocked by turning the handle 35; and the auxiliary frame, which is pivoted to the main frame 37 about an upright stud, not shown, at the rear of the machine, is swung to the left so as to give access to the feed roll. It is then necessary to loosen a collar, not shown, on the rod 7, which holds the carrier 5 from moving longitudinally of the rod, to withdraw the rod, one end of which is screwed into a bore in the auxiliary frame; and then, having disengaged the feed roll 9 from the short link 31, by swinging the feed roll down about the axis of its stem 17, to remove as a unit the carrier 5, the block 13 and the parts including the feed roll carried thereby. It is then possible to unscrew the small screw (corresponding to the screw 19), which holds the stem 17 in its socket, and to remove the feed roll assembly which consists of the block 13 and the feed roll mounted upon it. After the feed roll assembly has been replaced by another one, it is necessary to reverse the procedure described above, including screwing the rod 7 back into exactly the adjusted position which it occupied before, and refasten on the rod the collar referred to above which prevents longitudinal movement of the carrier 5 on the rod, and this procedure is hampered more or less by the fact that the cross pins at the ends of the link 31 are loose and are hence liable, during the handling of the link 31, to fall out of the holes or bores through which they pass. This partial dismantling and reassembling of the machine described above requires the services of a skilled mechanic, who is familiar with the machine and can accurately readjust the parts.

In order to facilitate removal and replacement of the feed roll assembly, the frame of the present machine is provided with an opening 32 in line with the stem 17 of the feed roll assembly; and the long screw 19 is provided, the head of which projects through the opening so as to be readily accessible. In order to prevent the falling out of the cross pins 30 when the link 31 is being handled, each cross pin is provided at its middle with a comparatively wide annular groove, into which extends one end of a small screw 39 so that the pins, while free to slide to some extent, cannot fall out of their bores.

When, now, it is desired to remove the feed roll assembly and replace it by one having a different feed roll, the auxiliary frame is swung out, the rod 23 is turned so as to swing the extended end

of the torsion spring 21 down out of the way; the feed roll 9 is swung down about the axis of its stem 17 to disengage it from the link 31, which may then be removed, the cross pins 30 remaining in place in the enlarged ends of the link; and then the screw 19 is unscrewed. The whole feed roll assembly may then be removed and replaced without removing the roll carrier 5, which remains in its adjusted position on the rod 7.

Having thus described my invention, what I claim as new and desire to secure by Letters Patent of the United States is:

1. A machine of the class described having in combination, a tubular knife, a feed roll located partly within the knife, a block upon which the feed roll is rotatably mounted, said block having a cylindrical stem about the axis of which the block and roll may be tilted, a spring for normally holding up one end of the feed roll, a link for driving the roll, said link having an enlarged end provided with a cross bore, a cross pin slideable in the bore, means for limiting said sliding movement, a carrier having a socket to receive the cylindrical stem of the block, there being in the frame of the machine an opening in line with the axis of the socket, and a screw for holding the stem in the socket, said screw having a head which extends out through said opening.

2. A machine of the class described having in combination a main frame, a tubular knife rotatably mounted in said main frame, an auxiliary frame pivoted to the main frame about a substantially vertical axis and capable of being swung out to expose the elements mounted in it, a feed roll normally located partly within the knife, a block upon which the feed roll is rotatably mounted, said block having a cylindrical stem about the axis of which the block and roll may be tilted, the block and roll forming a feed roll assembly, a spring for holding up one end of the block, means for mounting the spring in such manner that it may be withdrawn from contact with the block, a driving link having a readily separable universal-joint connection with the roll, an adjustable carrier mounted on the auxiliary frame and having a socket to receive the cylindrical stem of the block, and a screw for holding the stem in the socket, the frame of the machine having in it an opening in line with the screw whereby, after the auxiliary frame has been swung out, the feed roll assembly may be removed and replaced while retaining the carrier in its adjusted position.

EUGENE J. RAY.
